Primary Examiner — Robert M Spear*Assistant Examiner* — Marissa J Cash(74) *Attorney, Agent, or Firm* — R. Neil Sudol; Henry D. Coleman(57) **CLAIM**

The ornamental design for an ultrasonic surgical cutting blade, as shown and described.

DESCRIPTION

FIG. 1 is a top, front, and right side perspective view of a ultrasonic surgical cutting blade, showing our new design; FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines depict unclaimed subject matter and form no part of the claimed design.
